SIGNAL SYSTEM

William D. Lindsey, South Orange, N. J., assignor, by mesne assignments, to The Sealand Corporation, a corporation of Connecticut

Application October 11, 1933, Serial No. 693,052

1 Claim. (Cl. 177—355)

The invention herein disclosed relates to an electrical signal system for indicating the existence of several different conditions and in particular, the invention appertains to the operation, over a single pair of transmission lines, of various signals at a remote point, each signal having a different designated significance.

In certain signal systems, for example protective signal systems for property, it is desirable to indicate at a remote point not only the existence of a condition detrimental to the protected property but also a condition which would render the system ineffective to effectuate the actuation of the remote warning signal upon the existence of the condition against which the property is protected. Such an arrangement is particularly desirable in connection with automatic warning systems as, for example, a fire warning system. In such a system, the remote point is preferably 10 the fire engine house serving the locality in which the property to be protected is located. The signal to indicate the existence of a fire may be either audible or visual or both. In addition a 15 distinctly different signal either audible, visual or both, should be used to indicate a condition which would render the system ineffective to effectively operate or transmit a signal upon the existence of a fire at the property served by the system.

30 By this invention, several independent electrical signals are actuated at a remote point over a supervised transmission line made up of a single pair of wires. One signal may indicate the existence of some undesirable condition in a protected property, and another signal may indicate the failure or breakdown of the protective system and in addition another signal may be provided which is actuated upon the inability of the transmission line to transmit the variations 35 in energy necessary for the actuation of the warning signal and the other trouble signals. In accordance with the invention, a closed electrical circuit is utilized in conjunction with electrically actuated signals and means operative upon opening the circuit to effect the operation of one particular signal and operative upon shunting a portion of the circuit to effect the operation of another signal and operative upon successively opening and closing the circuit to effect the operation of a third signal. When this circuit is used in a protective signal system for protecting property, the signal operated by opening the circuit indicates trouble with the transmission line and the other signals indicate the existence 50 of the condition which is undesirable on the pro-

tected property and the inability of the system to function due to a defect in the portion of the system on the protected property.

In one form, the invention is embodied in a system for signaling the fire department upon the existence of a fire or abnormal thermal conditions on property in connection with which the system is used. Such a system may include as a portion thereof an automatic fire detecting system such as that disclosed in the copending application of William D. Lindsey, Serial No. 687,278, filed August 29, 1933, for Warning system, a code transmitter which upon actuation effects a circuit closer in accordance with a definite code, and another transmitter which actuates a circuit closer intermittently. The former code transmitter is utilized for effecting the production of electrical impulses in accordance with a predetermined code and thus effecting the operation of an audible signal in accordance with the code which definitely locates the property on which the abnormal thermal conditions exist. The latter transmitter is operative to effect a series of intermittent impulses. In the case where the signal system transmits a signal directly to a fire house 20 of the municipal fire department the impulses formed by the actuation of the transmitters are transmitted over a transmission line to the fire engine house, which transmission line consists of a single pair of wires. Located in the fire engine house there is a series of relays which are interconnected and mutually dependent in their operation. One of these relays constitutes a part of a closed electrical circuit which includes a source of electrical energy, the relay, and the 30 transmission line connecting the property equipped with the system and the fire engine house. The circuit closer of the code transmitter at the protected property shunts a portion of this circuit, and the circuit closing elements of the other transmitter successively opens and closes this circuit. The remaining relays of the electrically actuated means for effecting the operation of the trouble signals are interconnected with this relay and depend upon the operation of this relay for the energization thereof. When the circuit opens and remains open, the relay included as a part thereof becomes deenergized and effects the operation of other relays which in turn control particular signals. When the circuit is successively opened and closed, the relay in the circuit is successively deenergized and reenergized. This action through the interconnection of the other relays effects the operation of another independent and distinctly different 55

signal. The signals may be visual, audible or both.

When the code transmitter operates to shunt a portion of the closed circuit, it cuts out a certain amount of resistance and effects the operation of a normally inoperative relay included in the closed circuit. This normally inoperative relay operates in accordance with the impulses set up by the intermittent shunting of a portion of the closed circuit. The relay effects the operation of an audible and visual signal, the audible signal being operated in accordance with the action of the code transmitter which is reproduced in the relay contained in the closed circuit.

15 The fire system on the protected property may be manually or automatically operated. The manual operation effects the operation of the code transmitter. The operation of the same or a similar transmitter is effected automatically by 20 the automatic system in the event of the existence of abnormal thermal conditions. In the event of a condition existing in that portion of the system on the protected property which would render the system unable to operate effectively, the intermittently actuated transmitter is operated thus effecting the operation of a signal at a remote point which indicates that the portion of the system on the protected property is inoperative for the purpose intended. The various parts of the system are thus effectively supervised and continuous protection for the property on which the system is utilized is assured.

Where two or more distinctly different and 35 separated properties are to be protected by systems of this type, it is essential that under no conditions can the transmitters of two or more systems have simultaneous connection with the common audible signal for reproducing the code, 40 as this would result in a jumble of codes. The systems are therefore interconnected and include electrically actuated means for giving preferential control of the audible signal to the several systems in accordance with their rating as 45 fire hazards.

Two such interconnected systems are illustrated in the accompanying drawings in which the systems and their interconnection are illustrated diagrammatically by a line drawing in 50 Fig. 1 and by an across-the-line diagram in Figs. 2 and 3 and these systems are described in detail below. From this illustration and description a clearer understanding of the invention may be had.

55 The drawings illustrate two interconnected protective systems YY and ZZ. In the system ZZ, the fire detecting circuit located on the protected property is an electrically supervised automatically operative circuit. This circuit includes a battery 1 as a source of current and a fire relay 2 one side of which is connected to the positive side of the battery by a conductor A1. The other side of the fire relay 2 is connected through a conductor A2 to a supervisory relay 3 which is 60 connected in series with one end of an element A3 of a fire detecting cable 4 constructed as disclosed and described in the copending application Serial No. 352,624, filed April 5, 1929, for Cable and method of producing the same. The 65 other end of the element A3 is connected by a conductor A4 to one end of a resistance 4'. The other end of the resistance is connected by a conductor A5 to the end of an element A6 of the fire detecting cable corresponding to the end of 70 the element A3 to which the conductor A4 is con-

nected. The end of the element A6 corresponding to the end of the element A3 to which the conductor A2 is connected, is connected by a conductor A7 to the negative side of the battery 1. It will thus be seen that the fire circuit A is 5 a closed circuit including the relays 2, 3, the fire detecting cable 4 and the terminal resistance 4'. The relay 3 is such that it is normally actuated and due to the resistance 4' the relay 2 is normally inoperative. The elements A3 and A6 of 10 the fire detecting cable are juxtaposed normally insulated electrical conductors one of which upon the existence of abnormal thermal conditions fuses and becomes electrically connected to the other thus shunting the resistance 4'. When 15 this condition exists the resistance 4' is shunted out of the circuit and sufficient current flows through the relay 2 to actuate this relay. The same condition may be obtained by the actuation of a manual fire box represented diagrammatically at 5. This fire box is connected across the terminals of the cable 4 and when actuated connects these two terminals together, thus shunting out the resistance 4' and effecting the operation of the fire relay 2. If anything occurs which 20 opens the circuit A, the relay 3 is deenergized. Deenergization of this supervisory relay 3 effects, through the contacts thereof, the operation of local trouble signals on the protected property either audible or visual or both and a 30 transmitter. The manner in which the operation of the local trouble signals is effected is illustrated in the copending application Serial No. 687,278, filed August 29, 1933, and the manner in which the operation of the transmitter is 35 effected will be hereinafter described.

When the fire relay 2 is operated it completes, through contacts 2a and 2b thereof, a circuit to an electrically actuated, mechanically operated transmitter 6 mounted on a control panel. This 40 circuit B includes a conductor A1 which connects the positive side of a thirty-two volt battery 1 to the movable contact 2a which is actuated by the relay 2 and which cooperates with the fixed contact 2b. The contact 2b is connected by a 45 wire B2 to one side of the coil 6a of the transmitter 6. The other side of the coil 6a is connected by a wire B3 to a movable contact 6i of the transmitter 6 which is controlled by the relay coil 6a. The movable contact 6i cooperates with 50 a fixed contact 6j which is connected by a wire B4 to a negative line wire B5 that is connected in common to the negative terminals of the thirty-two volt battery 1 and a six volt battery 7. In addition to the fixed and movable contacts 6i and 55 6j, the relay 6 has other cooperating fixed and movable contacts 6b and 6c, 6d, 6e and 6f, and 6g and 6h the purpose of which will hereinafter appear.

A supervising relay 8 is connected across the 60 terminals of the thirty-two volt battery 1 and it is normally energized. One side of the relay is connected to the positive side of the battery by a wire C3 and the other side of the relay winding is connected to the negative side of the 65 battery by a wire C4. If for any reason the battery fails and there is not sufficient power for operating the system, the relay winding 8 becomes deenergized and the fixed and movable contacts 8a and 8b thereof are closed. The fixed 70 and movable contacts 8a and 8b are connected into a circuit which controls the energization of a transmitter 9. This circuit D includes a conductor D1 connecting the movable contact 8b to the positive side of the six volt battery 7, and 75

a conductor D2 connecting the stationary contact 3a to one side of the coil 9a of the transmitter 9. The other side of the coil of the transmitter 9 is connected through a conductor D3 to a movable contact 9i of the transmitter which contact is actuated by the coil 9a and cooperates with the fixed contact 9j. The fixed contact 9j is connected by a conductor D4 to the negative line wire B5 and thus to the negative side of the 10 battery 7. Upon failure of the thirty-two volt battery 1, therefore, the six volt battery 7 supplies a current to the coil 9a of the transmitter 9. This current is sufficient to actuate this transmitter. The transmitter includes in addition to 15 the contacts 9i and 9j, fixed and movable contacts 9b and 9c, 9d, 9e and 9f, and 9g and 9h which are all actuated by the coil 9a of the transmitter and the purpose of which will hereinafter appear.

20 As heretofore stated, the supervisory relay 3 becomes deenergized when the fire circuit is opened, that is, when such a condition exists that would render the fire circuit inoperative for detecting abnormal thermal conditions, and effecting the operation of the signals. This relay includes a pair of cooperating movable and fixed contacts 3a and 3b which control the energization of a transmitter 10. The contacts 3a and 3b are normally separated by the energization 25 of the relay and maintain a circuit E open. The circuit E includes a conductor E1 which connects the movable contact 3a to the positive side of the thirty-two volt battery 1, and a conductor E2 which connects the stationary contact 3b to one side of the coil 10a of the transmitter 10. Thus when the contacts 3a and 3b are closed by virtue of the deenergization of relay 3, the coil 10a of the relay is connected to the positive side of the thirty-two volt battery. The other side of 30 the coil 10a of the relay 10 is connected to the negative side of the battery through a conductor E3, a movable contact 10i of the transmitter 10, a stationary contact 10j contacting with the contact 10i and a conductor E4 which connects the stationary contact 10j to the negative wire B5. The contacts 10i and 10j are normally closed and are opened upon the energization of the 35 relay coil 10a. This arrangement effects an intermittent operation of the relay. In addition to the contacts 10i and 10j, the relay 10 includes cooperating stationary and movable contacts 10b and 10c, and 10d, 10e and 10f, and 10g and 10h. These latter cooperating contacts control 40 circuits which will hereinafter be described. It will be evident from the description of this circuit that upon deenergization of the relay 3, that is, upon a break existing in the local system within the protected property which is detrimental to the proper operation of the fire circuit, the transmitter 10 is operated.

One of the effects of the operation of the transmitter 10 is the operation of a remote trouble bell 11. The local trouble signals on the protected property are normally grouped together 45 in a place where they are visible during the time the building is occupied. These trouble signals include all of the supervisory signals including the signals for trouble in the lights and other elements of the system. For example, in a school, these trouble signals would be located in the principal's office. However, when the building is not occupied, there is no one at hand to respond to these trouble signals except the watchman or janitor. The remote trouble bell 11 is therefore provided for indicating trouble which

would impair the ability of the system to effect the operation of the signal in the fire engine house. The remote trouble bell 11 is therefore controlled by the transmitter 10 and the circuit for controlling this remote trouble bell through 5 the transmitter 10 includes a conductor F1, which connects the stationary contact 10f of the transmitter 10 to the positive side of the battery 1 through a resistance 12. The remote trouble bell, however, operates on six volts and the resistance 10 12 is therefore provided to cut down the voltage supplied to the trouble bell when it is actuated by the transmitter 10. In the circuit F, the movable contact 10g is connected to a conductor F2 which is connected to one side of the remote 15 trouble bell 11. The movable contact 10g is normally in contact with stationary contact 10h. This stationary contact 10h is connected through a conductor F3 to the movable contact 9g of the transmitter 9. The movable contact 9g is normally in contact with the stationary contact 9h which is connected by a conductor F4 to one side of the coil of a relay 13. The relay 13 is connected to the conductor F4 through a resistance 14 which cuts down the current normally supplied to the coil of the relay. The other side of the coil of this relay is connected through a conductor F5 to the positive wire F1. A conductor F6 connects the trouble bell 11 to the negative line wire B5. It will be apparent from 20 this description that there is a closed circuit through the trouble bell and relay winding 13 as follows: positive terminal of the thirty-two volt battery, conductor F1, conductor F5, the coil of relay 13, resistance 14, conductor F4, stationary 25 contact 9h of transmitter 9, movable contact 9g, conductor F3, stationary contact 10h of transmitter 10, movable contact 10g, conductor F2, remote trouble bell 11, conductor F6, and negative conductor B5 to the negative side of the 30 thirty-two volt battery. The resistance of this circuit is such that the current flowing therethrough is insufficient to operate the bell 11. It is, however, sufficient to energize the relay winding 13. Upon the actuation of the transmitter 40 10, however, the contact 10g is moved into engagement with the contact 10f thus connecting the wire F2 to the positive side of the thirty-two volt battery through the resistance 12. There is then a direct circuit through the remote trouble 45 bell which causes that bell to be actuated, the relay winding 13 being opened. This circuit includes the thirty-two volt battery, the wire F1 connecting the positive side thereof, resistance 12, stationary contact 10f, movable contact 10g, 50 wire F2, remote trouble bell 11, wire F6 and negative wire B5. The remote trouble bell is thus actuated upon the operation of the transmitter 10.

The remote trouble bell is also actuated upon 55 the operation of the transmitter 9. When the transmitter 9 is operated, the movable contact 9g is separated from the stationary contact 9h and brought into engagement with the stationary contact 9f. The stationary contact 9f is connected 60 through a wire F7 to the positive side of the six volt battery. Consequently, when the transmitter operates and the contacts 9g and 9f are brought together, there is a direct circuit through the trouble bell and the six volt battery which is 65 as follows: the positive side of the six volt battery, wire F1, contact 9f of transmitter 9, movable contact 9g, wire F3, stationary contact 10h of transmitter 10, movable contact 10g of transmitter 10, wire F2, remote trouble bell 11, and wire 70 75

F6 to the common negative line wire B5. Thus, the remote trouble bell is also actuated when there is a failure of the thirty-two volt battery.

The closed circuit described above which includes the remote trouble bell is a supervisory circuit. As heretofore stated, if this circuit is opened for any reason such as the breaking of a conductor or an open circuit in the trouble bell, the relay 13 is deenergized. This relay controls a set of fixed and movable contacts 13a and 13b which are in the circuit of a trouble lamp 14 which upon being illuminated indicates that there is trouble in the remote trouble bell circuit. The circuit to the trouble light includes the conductor F1 which is connected to the positive side of the battery, the conductor F5 connecting the conductor F1 to one side of the relay 13, a conductor G1 connecting the movable contact 13a of the relay 13 to the conductor F5, a conductor G2 connecting the stationary contact 13b to the trouble light 14 and a conductor G3 connecting the trouble light to the common negative conductor B5. It will be obvious that upon the deenergization of the relay 13 and the engagement of the contacts 13a and 13b the trouble light 14 will be connected across the thirty-two volt battery. Obviously this relay can also be used to operate an audible signal in addition to the visual signal represented by the light 14.

In conjunction with the transmitters 6, 9 and 10, there is a transmitter 15 which is manually operated and preferably mounted on the outside of the building protected by the system. The transmitter 15 is a code transmitter similar to the transmitter 6 in that it transmits a series of impulses in accordance with the predetermined code. The code may also include an added element or impulse to indicate to the fire department that the call has been initiated by the outside transmitter. It is advisable, in these systems, to let the fire department know whether it is an outside or inside call. If it is an inside call then they can determine the exact location of the call from the panel board, particularly if the building protected is divided up into a series of zones. The transmitter 15 includes a pair of normally open stationary and movable contacts 15a and 15b. These contacts are successively closed and opened in accordance with a predetermined code when the transmitter is manually set into operation. The movement of the movable contact 15b to close and open the circuit is accomplished through a spring wound motor, not shown. Across the contacts 15a and 15b there is connected a resistance 15c.

The transmitter 15 forms in effect the end of a transmission line circuit extending from the protected property in which the several transmitters 6, 9 and 10 are located to the fire engine house serving the locality in which the protected property is located. This transmission circuit is a closed circuit and includes a twelve volt battery 16 as a source of electrical energy. The twelve volt battery is located in the fire engine house and is connected to terminals 16a and 16b on a panel 17 which is also located in the fire engine house and mounted in a place where it is readily visible. The positive terminal 16a is connected through a wire H1 to a connector 18a to which is also connected one end of a transmission line wire H2. The other end of the transmission line wire is connected to the contact 6b of the transmitter 6. A branch conductor H3 connects the line wire H2 to the contact 10b of the transmitter 10. The movable contact 10c which cooperates

with the stationary contact 10b and which is normally in engagement therewith is connected by a conductor H4 to the stationary contact 9b of the transmitter 9. The movable contact 9c of the transmitter 9 which normally engages the fixed contact 9b is connected through a conductor H5 to one side of the code transmitter 15. The other side of the code transmitter 15 is connected by a conductor H6 to the fixed terminal 6f of the transmitter 6. The fixed contact 6f of the transmitter 6 is normally in contact with the movable contact 6e which is connected by a conductor H7 to one end of the transmission line wire H8 which is connected in common to the movable contacts 6c and 6e of the transmitter 6. The transmission line wire H8 connects these contacts to a contact 18b on the panel 17 in the fire engine house. The contact 18b is connected through a wire H9 to one side of the coil of a relay 19. The other side of the relay is connected through a wire H10 to one side of the coil of another relay 20. This latter relay is connected through a wire H11 to a negative line wire H12 which is connected to the negative terminal 16b. It will thus be apparent that there is a closed circuit including the transmission line wires as follows: battery terminal 16a, positive line wire H1, terminal 18a, transmission line wire H2, conductor H3, fixed and movable contacts 10b and 10c of transmitter 10, conductor H4, fixed and movable contacts 9b and 9c of transmitter 9, conductor H5, resistance 15c connected across the terminals 15a and 15b of transmitter 15, conductor H6, normally closed fixed and movable contacts 6f and 6e of transmitter 6, conductor H7, line wire H8, connector 18b, conductor H9, the coil of relay 19, conductor H10, the coil of relay 20, conductor H11, and negative line wire H12. The resistance 15c is sufficient to reduce the current in this circuit so that the relay 20 is normally not operated. The relay 19 is however normally operated and controls circuits which will hereinafter be particularly described.

The transmitters 6 and 15 operate to intermittently shunt the resistance 15c out of the circuit in accordance with a predetermined code, thus effecting the intermittent energization and deenergization of the relay 20. With the transmitter 15 this is accomplished by merely bringing together the contacts 15a and 15b. It will be apparent that when these two contacts are connected together the wires H5 and H6 are directly connected and the resistance 15c is shunted out of the circuit. The same effect is obtained when the transmitter 6 is operated. The first thing that transpires upon the energization of the coil of transmitter 6 is that the contacts 6b and 6c close. Thereafter contacts 6e and 6f open and contacts 6e and 6d close, while contacts 6b and 6c are still closed. When the transmitter 6 is operated the transmitter 15 and resistance 15c are cut out of the circuit by the opening of contacts 6e and 6f. Upon the opening of contacts 6b and 6c, the circuit including the line wires H2 and H8 is therefore completed through a resistance 21 so as not to leave the circuit open. The closed circuit is then through the contacts 6e and 6d as follows: line wire H2, conductor H3, resistance 21 which is connected between conductor H3 and contact 6d, movable contact 6e, wire H7 and wire H8. The transmitter 15 is cut out of the circuit upon the operation of transmitter 6 to prevent any interference by it in the operation of the transmitter 6. The contacts 6i and 6j open and close in accordance with the operation of the transmitter and serve to restore the line 75

upon the completion of the operation of the transmitter.

The operation of the transmitter 6 is effected electrically but the operation is continued mechanically, a spring motor furnishing the power. When the transmitter is operated, the contacts 6h and 6g are closed. These contacts close a circuit to a light 22 which indicates that the transmitter should be rewound. This light remains lighted until the transmitter has been rewound and placed in condition for repeated operation. The circuit to the light includes a wire I1 which is connected to the wire F1 which as heretofore described is connected to the positive side of the thirty-two volt battery. Wire I1 is also connected to the movable contact 6h. Thus, upon the closing of the contacts 6h and 6g, contact 6g is connected to the positive side of the battery. The contact 6g is connected to one side of the light 22 by a wire I2, and the other side of the light 22 is connected by a wire I3 to the negative line wire B5.

The transmitter 10 when actuated causes a series of intermittent successive openings and closings of the transmission circuit. The opening and closing of this circuit is accomplished through the normally closed contacts 10b and 10c which as heretofore described, form a part of the circuit connecting the conductors H3 and H4. When the circuit is opened and closed, it effects the successive deenergization and reenergization of the relay 19. The transmitter 10 which is operated by a spring motor also includes a rewind signal light 23. This rewind signal light is connected in a circuit which includes the wire F1 which is connected to the movable contact 10e of the transmitter 10 and a conductor J1 which connects the stationary contact 10d that cooperates with the movable contact 10e to one side of the light 23. The other side of the light 23 is connected by a conductor J2 to the negative line wire B5. Upon operation of the transmitter the conductors 10e and 10d are placed in engagement and the circuit to the light 23 is completed. This circuit remains completed until the transmitter is rewound and placed in condition for operation.

The transmitter 9 is identically the same as the transmitter 10. In the transmitter 9 the normally closed fixed and movable contacts 11b and 11c are, as heretofore described, connected in series in the transmission circuit H. Upon the operation of the transmitter these contacts are opened and closed intermittently. The opening and closing of the contacts do not follow any particular code but merely consists of successive separations and engagements of the contacts. Like the transmitter 10, the transmitter 9 includes a signal light 24 for indicating that the transmitter has been operated and should be rewound. The circuit for this signal light includes the fixed and movable contacts 9d and 9e of the transmitter 9. The movable contact 9e is connected to the wire F7 which as heretofore described is connected to the positive side of the six volt battery, the contactors 9e and 9f being connected in common to the wire F7. The stationary contact 9d cooperating with the movable contact 9e is connected by a conductor K1 to one side of the light 24. The other side of the light 24 is connected by a conductor K2 to the negative line wire B5. Upon the operation of the transmitter contacts 9d and 9e are brought into engagement and the circuit to the light 24 is completed through the six volt battery. As heretofore

described, this transmitter operates when the thirty-two volt battery fails. For this reason its rewind light is taken from the six volt battery by which the transmitter itself is operated.

The successive opening and closing of the circuit H and the intermittent shunting of a portion of the circuit effect the operation of a series of relays including the relays 19 and 20 for the purpose of operating several independent signals to indicate at the fire engine house trouble in the fire circuit of the protected property, failure of the thirty-two volt battery, and trouble in the transmission line extending between the protected property and the fire engine house. When either the transmitter 6 or 10 operates to shunt out a portion of the resistance of the circuit H, the relay 20 is operated in accordance with the operation of the transmitter. Each time the contacts of the transmitters close and cut out the resistance, an impulse of current of sufficient magnitude to operate the relay 20 passes through the circuit H and causes the full energization of the coil of this relay. When the contacts open the coil of the relay becomes partially deenergized and releases its movable contacts 20a and 20b. The cooperating movable and fixed contacts 20a and 20b of the relay 20 are normally open and are closed when the coil of the relay 20 is fully energized. These two contacts are included in a circuit to a relay 25 which controls the actuation of two gongs 26 and 27, one located in the fire engine house containing the panel 17, and the other located elsewhere. The circuit to the relay 25 includes a positive line wire L1 which at one end is connected to the positive terminal 16a on the panel 17. A conductor L2 connects the movable contact 28'f of a relay 28' in the system ZZ to the line wire L1. A cooperating fixed contact 28'g of the relay 28' which is normally in engagement with the movable contact 28'f is connected by a conductor L3 to a conductor L4 which is also connected to the movable contact 20a of the relay 20. Thus the contact 20a is connected to the positive side of the twelve volt battery. The fixed contact 20b is connected by a conductor L5 to one side of the coil of the relay 25. The other side of the coil of the relay 25 is connected by a conductor L6 to the negative conductor H12. When the relay 20 is fully energized and the contacts 20a and 20b are in contact a circuit is completed to the relay 25 as follows: positive terminal 16a, positive line wire L1, conductor L2, movable contact 28'f of relay 28', fixed contact 28'g of relay 28', conductor L3, conductor L4, movable contact 20a of relay 20, cooperating fixed contact 20b, conductor L5, relay 25 and conductor L6 to the negative conductor H12 and thus to the negative connector 16b. The relay 25 includes a pair of movable and fixed contacts 25a and 25b and 25c and 25d. The cooperating movable and fixed contacts 25a and 25b are in a circuit which includes the gong 26. This circuit includes a conductor M1 which connects the gong to the positive line wire through a gong connector 26a on the panel 17. The other side of the gong is connected through a connector 26b on the panel 17 to a conductor M2 which is also connected to the fixed contactor 25b of the relay 25. The cooperating movable contactor 25a is connected by a conductor M3 to the negative line wire H12. Upon the operation of the relay 25 the movable contact 25a engages the fixed contact 25b and the circuit is completed from the battery 16 to the gong 26 as follows: Line wire, wire M1, gong 26, conductor 75

M2, contact 25b, contact 25a and negative line wire H12. A similar circuit includes the gong 27. This circuit consists of a wire N1 connecting one side of the gong to the positive line wire through a connector 27a on the panel 17. The other side of the gong is connected through a connector 27b to a conductor N2 which is also connected to the fixed contact 25d of the relay 25. The movable contact 25c cooperating with the fixed contact 25d is connected by a conductor N3 to the negative line wire H12. The gongs 26 and 27 are of course merely representative of audible signals and may be sirens or any other like signal.

15 The relay 20 also includes cooperating fixed and movable contacts 20c and 20d which are normally separated and which are connected upon the full energization of the relay. These contactors are included in a circuit in which is included a relay 28 which controls a visual signal represented by a lamp 29. The circuit to the relay 28 includes the positive line wire L1, a wire O1 which connects the positive line wire L1 to the movable contact 20d, a wire O2 which connects the stationary contact 20c to one side of the relay 28, and a conductor O3 which connects the other side of the relay 28 to one terminal of a reset switch 30 which includes fixed and movable contactors 30a and 30b that are normally closed and included in the circuit to the relay 28. The conductor O3 is connected to the fixed contactor 30a of the reset switch, and the movable contactor 30b is connected through a conductor O4 to the negative line wire H12. When the relay 28 is thus energized it completes a holding-in circuit so that it remains energized irrespective of the subsequent deenergization of the relay 20. This holding-in circuit includes a conductor O5 which is connected to a movable contact 28c. The movable contact 28c cooperates with a fixed contact 28d which is connected to the conductor O2. Upon energization of the relay 28 the circuit through that relay is completed through the contacts 28c and 28d and is independent of the relay 20.

As heretofore stated, operation of the relay 28 effects the energization of the light 29 to provide a visual signal. This is accomplished in part through the operation of a fire lamp relay 31 which is energized upon the energization of the relay 28. The circuit for energizing this fire lamp relay includes a conductor P1 which connects the positive line wire L1 to a movable contact 28a on the relay 28. The movable contact is normally separated from a cooperating fixed contact 28b to which it is connected upon energization of the relay. This fixed contact 28b is connected by a conductor P2 to one side of the coil of the relay 31. The other side of the 50 coil of the relay 31 is directly connected through a wire P3 to the negative line wire H12. It will be seen that this circuit to the relay 31 is closed upon the energization of the relay 28.

The relay 31 includes a movable contact 31a which cooperates with two fixed contacts 31b and 31c. The fixed contact 31b which is normally separated from the movable contact 31a is connected by a conductor Q1 to the negative line wire H12. The movable contactor which is connected to the fixed contact 31b upon energization of the relay is connected through a conductor Q2 to one side of the light 29. The other side of the light 29 is connected by a wire Q3 to a fixed contact 28e of the relay 28. This 65 fixed contact cooperates with a movable contact

28f to which it is connected when the relay 28 is energized. The contact 28f is directly connected through a wire Q4 to the positive line wire L1. Thus, upon energization of the relay 28, the relay 31 is operated and through the closing of the contacts 28e and 28f of the relay 28 and the contacts 31a and 31b of the relay 31, the light 29 is energized and provides a visual signal indicating the origin of the fire. This signal it will be understood is individual to a particular property that is protected by the system YY and consequently affords a visual signal designating the location of the fire. The gongs operated in accordance with the code also designate the location of the fire by an audible signal which may be interpreted but the light 29 provides an immediate signal at the fire engine house wherein it is located and there is no necessity for the men to await the completion of the code on the audible signal. Since relay 28 is locked, the light also provides a continuous designating signal after the audible signal has become dormant.

As heretofore stated, the relay 19 is normally energized and becomes deenergized when the circuit H is opened. This relay includes cooperating fixed and movable contactors 19a and 19b which are normally separated. Upon deenergization of the relay these contactors are connected and complete a circuit to a relay 32. The circuit to the relay 32 includes the negative line wire H12 and a conductor R1 connecting the negative line wire to the movable contact 19b. The fixed contact 19a is connected by a conductor R2 to movable contact 33a of another relay 33. This movable contact 33a is normally in contact with a fixed contact 33b which is connected by a conductor R3 to one side of the coil of the relay 32. The other side of the coil of the relay 32 is connected through a conductor R4 to the positive line wire L1 and to the positive terminal 16a. Thus, when the circuit H is opened the coil of the relay 32 is energized.

The relay 32 has two pairs of fixed and movable contacts 32a and 32b, 32c and 32d. One pair of these contacts, that is, contacts 32a and 32b, control a circuit to a trouble light 34. This circuit includes a conductor S1 which is connected to the positive side of the twelve volt battery through the conductors R4 and L1 to which it is connected, a conductor S2 connecting the conductor S1 to one side of the trouble lamp, and a conductor S3 which connects the other side of the trouble light to the stationary conductor 32b of the relay 32. The cooperating movable contactor 32a of the relay 32 is connected through a conductor S4 to the conductor O4 and thus to the negative line wire H12. The circuit to the light is therefore completed upon the energization of the relay 32. This trouble light 34 indicates that there is trouble in the transmission line and that a signal can not be transmitted over the line.

The contacts 32d and 32c of the relay 32 are included in a circuit to a trouble bell 35 and upon contacting when the relay 32 is energized complete the circuit to the trouble bell so that there is an audible as well as a visual signal indicating trouble in the transmission line. The circuit to the bell includes a conductor T1 which connects one side of the bell to the conductor S1 and thus to the positive side of the twelve volt battery, a conductor T2 which connects the other side of the bell to the stationary contact 32c of the relay 32 and a conductor T3 which connects the cooperat- 75

ing movable contact 32d to the conductor S4 and thus to the conductor O4 and the negative line wire H12. It will be apparent, therefore, that upon the energization of the relay 32 both the visual signal 34 and the audible signal 35 are actuated.

If the transmission circuit H is opened and closed in accordance with the operation of either of the transmitters 9 or 10, the relay 19 is successively deenergized and energized in accordance with the intermittent operation of the transmitter. When the relay 19 is deenergized, in addition to completing the circuit to the relay 32 it completes a circuit to a relay 36. This circuit to the relay 36 includes a wire U1 which connects a movable contact 19e on the relay 19 to the positive line wire L1. The contactor 19e cooperates with a stationary contact 19f from which it is normally separated but with which it is connected upon the deenergization of the relay 19. The contactor 19f is connected by a conductor U2, which has an interposed resistance 37, to one side of the relay 36. The other side of the relay 36 is connected by a conductor U3 to a stationary contactor 30c of the reset switch 30. The contact 30c cooperates with a movable contactor 30d which is connected by a conductor U4 to the wire O4 and thus to the negative line wire L7. The relay 36 is thus connected through the reset switch 30 in a closed circuit upon the deenergization of the relay 19. Upon energization of the relay 36, the relay closes a hold-in circuit which includes a conductor U5 that connects a movable contactor 35 36d to the conductor R4 and thus to the positive side of the battery. The conductor U2 has connected thereto a stationary contactor 36c which engages the movable contactor 36d when the relay 36 is energized. The relay 36 then becomes independent of the action of the relay 19.

The relay 36 also includes a pair of movable and fixed contactors 36a and 36b which control a circuit to a reset light 38. This circuit includes the conductor S1 which is connected to the positive side of the battery, a conductor V1 which connects the conductor S1 to one side of the light 38, and a conductor V2 which connects the other side of the lamp to the stationary contact 36b of the relay 36. The cooperating movable contact 36a which engages the contact 36b upon energization of the relay 36 is connected by a conductor V3 to a conductor S4 which in turn is connected to the conductor O4 and thus to the negative line wire H12. The reset lamp is thus lighted to indicate that the relays have been operated and should be reset. The contacting of contacts 36a and 36b of relay 36 also connects a conductor W1 to the wire V3 and thus to the negative side of the battery. The conductor W1 is also connected to a movable contactor 19c which cooperates with a fixed contactor 19d of the relay 19. Upon the reenergization of the relay 19 the circuit to the relay 32 is broken. Thus this relay becomes deenergized and also the trouble light 34 becomes deenergized.

On the reenergization of the relay 19 by the successive opening and closing of the circuit H the contactor 19c of the relay 19 which is now connected through the contacts 36b and 36a of relay 36, energized through its hold-in circuit, and the conductor V3 to the negative side of the battery, engages the contactor 19d of the relay 19. This latter contact is connected through a conductor W2 to one side of the coil of the

relay 33. The other side of the coil of the relay 33 is connected to the conductor R4 and thus to the positive side of the battery. It will therefore be evident that upon the reenergization of the relay 19 the relay 33 becomes energized. This relay upon becoming energized closes a hold-in circuit which includes fixed and movable contacts 33e and 33f of the relay 33. The contact 33f is directly connected to the conductor W2, and the stationary contactor 33e is connected by a conductor W4 to the wire U3 and thus through the reset switch to the wire O4 and the negative side of the battery. The closing of the contactors 33e and 33f therefore renders the energization of the relay 33 independent of the relay 19. Upon the energization of the relay 33 contacts 33a and 33b thereof are opened and thus prevent the completion of the circuit to the relay 32 upon the relay 19 becoming again deenergized in accordance with the intermittent operation of either transmitters 9 and 10. Thus, upon the successive opening and closing of the circuit H, the relay 32 is deenergized preventing the operation of the trouble light 34.

However, upon the operation of relay 33 a trouble light 39 is energized to indicate that there is trouble in that portion of the system within the protected property. The circuit to this trouble light includes a conductor X1 which is connected to the conductor S1 and thus to the positive side of the battery, the light 39 to which the conductor X1 is also connected, a conductor X2 which connects the lamp to a stationary contactor 33d on the relay 33, a movable contactor 33c which cooperates with the contactor 33d and engages this contactor when the relay is energized, and a conductor X3 which connects the movable contactor 33c to the conductor V4 and thus the conductor O4 and negative line wire H12. The stationary and movable contactors 33g and 33h of the relay 33 serve upon being engaged by the energization of the relay to complete a circuit to the trouble bell 35. This circuit includes the wire T1 through which one side of the trouble bell is connected to the positive side of the twelve volt battery, the conductor T2, and a conductor T4 which connects the conductor T2 and the stationary contactor 33g. Movable contactor 33h is connected by a conductor T5 to the conductor V4 and thus to the conductor O4 and the negative line wire H12. The operation of the relay 33 by the successive deenergization and reenergization of relay 19 effects through these circuits the operation of the trouble bell 35 and the trouble light 39, the trouble bell indicating audibly that trouble exists in the system, and the trouble light definitely locating the trouble to be in that portion of the system located upon the protected property.

It is to be noted that the relays 28, 33 and 36 when operated are connected to the source of energy, that is, the twelve volt battery, through the reset switch 30. After the trouble in the line has been located or the fire extinguished, the reset switch is manually actuated so that the movable contact 30d is separated from the movable contact 30c and the movable contactor 30b is separated from the stationary contact 30a thus breaking the circuits to these three relays. When the circuits are broken to these relays they become deenergized and restored to their normal or original position. When this is done the restore light controlled by relay 36 is extinguished. The restore light 39 indicates that one or the other of these relays 33 or 36 are operated.

It is also, in effect, a secondary supervisory light for the trouble lights 34 and 39 or a trouble light ancillary to the trouble lights 34 and 39 for if this restore light lights independently of the lights 34 and 39 it indicates trouble with the system and that one or the other of the trouble lights is inoperative.

Any number of similar systems may be used to protect various different properties. The systems for several such properties will be identical with that described immediately above. Several of such systems in a single locality will, however, be interconnected so that a single system of gongs will be actuated in common by the several circuits and several parts of the systems will be supervised in common. For the purpose of illustrating this interconnection, the illustrated embodiment of the invention includes the duplicate system ZZ on the panel at the fire engine house. The duplicate system ZZ includes the circuits H', I', J', etc. which are identical with the correspondingly designated circuits H, I, J, etc. of the system YY. The circuits of the system ZZ at the protected property have not been illustrated as there is no interconnection between this portion of the system. The circuit at the protected property for the circuit H' of system ZZ may be identical with that shown for the operation of the circuit H.

Since in a group of systems the single stroke gongs 26 and 27 are common to the several systems, it is necessary in order to prevent a jumble of the code signals by the simultaneous operation of both systems, to provide means for cutting out control of the gongs by all other systems when one system operates. In the system illustrated this is accomplished through the contacts 28'f and 28'g of the relay 28'. The systems are arranged in accordance with the possible fire hazard in the properties which they protect. In the illustrated case the system ZZ operated by the circuit H' is a greater fire hazard than the system YY. This system therefore is given preference over the system YY. Therefore the contactors 28'g and 28'f of the relay 28' control the connection of the contact 20a of the relay 20 which on engaging the contactor 20b, operates the gong relay 25. When the relay 28' operates, upon operation of relay 20' the movable contact 28'f is separated from the stationary contact 28'g thereby cutting the movable contact 20a of the relay 20 off from the conductor L2 and thus the positive side of the battery. The movable contact 28'f is on the other hand brought into contact with another stationary contact 28'e of the relay 28'. This contactor 28'e is connected by a conductor Y1 to the movable contact 20'a of the relay 20' thus connecting this movable contact to the positive side of the battery and rendering it ready to complete the circuit to the gong control relay 25, the stationary contact 20'b being connected to the wire L5 in common with the stationary contact 20b of the relay 20.

It is to be noted that it is only the control of the gong that is taken from the system YY upon the operation of the system ZZ. The fire lamp 29 is however operated so that there is a visual indication of a fire on the property protected by the system YY even though the system ZZ has control of the gong for sending an audible code signal.

The control circuit or the circuit for preventing interference is supervised so as to indicate a condition which would prevent any of the in-

terconnected systems from operating normally. This supervisory circuit includes a supervisory relay 40 which is connected in series with the contacts 28'f and 28'g of the coil of the relay 28'. The circuit to the relay includes the conductor L2, movable contact 28'f, the stationary contact 28'g, conductor L3, coil of the relay 40, and conductor H12. There is thus a complete circuit through the battery 16 and the coil of the relay 40 and this relay is normally energized. The relay 40 contains two pairs of fixed and movable contacts 40a and 40b and 40c and 40d. The contacts 40a and 40b are in a circuit which includes the trouble bell 35 so that when the coil of the relay 40 becomes deenergized as, for example, by the accidental opening of the contacts 28'f and 28'g, a circuit is completed to the trouble bell 35 which is operated to give an audible trouble signal. The circuit to this trouble bell includes a conductor Z1 which is connected to the negative line wire H12, a movable contact 31d on the relay 31, a fixed contact 31e of the relay 31 which is normally in engagement with the movable contact 31d and a conductor Z2 which connects the stationary contact 31e to the movable contact 40d of the relay 40. The cooperating fixed contact 40c of the relay 40 is connected to a conductor Z3 which is connected to the conductor T2 which latter conductor is, as heretofore described, connected to one side of the trouble bell 35. It will be apparent that upon operation of the relay 40, the side of the trouble bell to which the wire T2 is connected will be connected to the negative side of the twelve volt battery. The other side of the trouble bell is, as heretofore described, permanently connected to the positive side of the battery. Thus the operation of the trouble bell is effected upon the deenergization of the relay 40. It is to be noted that the operation of the trouble bell is dependent upon the continued in-operation of the fire lamp relay 31. When this is operated the circuit connecting the movable contact 40d to the negative side of the battery is broken at the contacts 31d and 31e. In the event of an actual fire operating the relay 28' and the relay 31, the trouble bell will not be operated due to a break in the circuit to the relay 40.

In addition to the audible trouble bell 35, a visual signal 41 is energized and specifically indicates trouble with this non-interference circuit. The circuit to the lamp 41 includes the conductor Z1, the contacts 31d and 31e of the relay 31, the conductor Z2, and a conductor AA1 which connects the conductor Z2 to the movable contact 40b thus connecting the movable contact 40b to the negative side of the twelve volt battery. The stationary contact 40a cooperating with the movable contact 40b is connected by a conductor AA2 to one side of the light 41 and the other side of the light 41 is connected by a conductor AA3 to the positive line wire S1 and thus to the positive side of the battery. It will therefore be apparent that upon the engagement of the contacts 40a and 40b while the relay 31 remains deenergized a circuit through the lamp 41 and the battery 12 will be completed thus lighting the light and providing the specific visual signal.

Electrical supervision is also provided for the gongs 26 and 27. The supervisory circuit for the gong 26 includes the positive line wire H1, the conductor M1 connecting the connector 26a, the gong 26, the connector 26b, conductor M2, 75

a conductor AB1 which connects the conductor M2 to one side of the coil of a supervisory relay 42, and a conductor AB2 which connects the other side of the coil of the supervisory relay 42 to the negative line wire H12. This is a complete closed circuit through the gong 26 and the relay 42 and including the battery 16. If this circuit is open for any reason the relay 42 becomes deenergized. The relay 42 upon becoming deenergized permits the contacting of two pair of fixed and movable contacts 42a and 42b and 42c and 42d. The fixed and movable contacts 42c and 42d are in a circuit which includes the trouble gong 35. This circuit includes the conductor M3 which connects the movable contact 25a of the relay 25 to the negative side of the battery, a contactor 25e which normally engages the movable contactor 25a and a conductor AC1 which connects the stationary contact 25e of the relay 25 to the movable contactor 42d of the relay 42. The contact 42c which cooperates with the contact 42d is connected to the conductor Z3 and thus to one side of the trouble bell 35 as heretofore described. Upon the engagement of the contactors 42d and 42c while the relay 25 is inoperative, the wire Z3 is connected to the negative side of the battery and as a consequence completing a circuit through the common trouble bell. The contacts 42a and 42b are connected into a circuit with a trouble light 43 which is illuminated upon the deenergization of the relay 42. This circuit includes the conductor M3, the movable and fixed contacts 25a and 25e of the relay 25, the conductor AC1, a conductor AD1 which connects the movable contact 42b with the conductor AC1, a conductor AD2 which connects the fixed contact 42a with one side of the light 43 and a conductor AD3 which connects the other side of the light 43 to the conductor AA3 and thus to the positive side of the battery. The light 43 and the trouble bell 35 furnish audible and visual trouble signals upon the opening of the gong circuit. The audible signal calls the attention of any one in the vicinity to the fact that trouble exists in the system and the visual signal definitely locates the circuit in which the trouble exists.

A similar supervisory circuit is used for supervising the gong 27. This circuit includes a relay 42' and a trouble light 43'. The connections through this latter relay are similar to those described in conjunction with the gong 26 and are similarly marked, the characters for designating the latter circuit are primed to distinguish them from the former.

The fire lights 29 and 29' of the systems YY and ZZ respectively, which are energized upon the existence of a fire or the coming in of a fire signal, are electrically supervised. The lights of the systems YY and ZZ are interconnected for the purpose of this supervision and the supervisory circuit includes both of these lights and a supervisory relay 44. This supervisory relay includes the conductor L1 which is connected to the positive side of the twelve volt battery 16, a conductor AE1 which connects the conductor L1 and one side of the relay 44, a conductor AE2 which connects the other side of the relay 44 and the conductor Q3 which is connected to one side of the fire light 29, the conductor Q2 which connects the other side of the light 29 to the movable contact 31a of the fire lamp control relay 31, a conductor AE3 which connects a stationary contact 31c, which cooperates with the

contact 31a and is normally in engagement therewith, to the conductor Q'3 of the system ZZ which is connected to one side of the light 29' and the conductor Q'2 which connects the other side of the light 29' to the negative line wire H12. The several conductors, contactors, relays and lights form a normally closed circuit including the battery 16 which circuit is opened upon the actuation of the relay 31. This closed circuit provides a supervisory circuit including the normally energized relay 44.

Upon the existence of any trouble in this circuit the relay 44 becomes deenergized and upon being deenergized effects the operation of the common trouble bell 35 and a distinctive trouble light 45. The circuit to the trouble bell includes the conductor Z1, the normally closed fixed and stationary contacts 31d and 31e of the relay 31, the conductor Z2, a conductor AF1 which connects the conductor Z2 and a movable contact 44d of the relay 44, which cooperates with a fixed contact 44c which is connected in common to the conductor Z3 with the contacts 40c, 42c and 42'c. As heretofore described the connection to the conductor Z3 to the conductor Z2 completes a circuit through the trouble bell 35 which effects the operation of that bell. The audible signal is therefore effected upon the deenergization of the relay 44. Similarly, the light 45 is lighted. The circuit to this light includes the connection with the negative side of the battery including the conductors Z1 and Z2 and the conductor AF1, a conductor AG1 which connects the conductor AF1 to a movable contact 44b of the relay 44 that cooperates with a fixed contact 44a, a conductor AG2 which connects the stationary contact 44a with one side of the light 45 and a conductor AG3 which connects the other side of the light to the positive conductor AA3. Through this circuit the trouble fire lamp is also lighted upon the deenergization of the relay 44 giving a visual signal which designates the exact circuit in which the trouble occurred, that is, the circuit including the fire lamp. It will be observed that the filaments of the fire lamps are supervised by this circuit as the circuit includes these filaments. Consequently, if a filament is broken or burns out the trouble signals are operated. The resistance of the supervisory circuit is such that the filaments are not heated by the current flowing therethrough.

A six volt battery 46 is provided for supervisory purposes. This battery is connected to terminals 46a and 46b on the panel 17. The six volt battery provides among other things the current for operating the signals upon the failure of the twelve volt battery. The twelve volt battery is supervised by a supervisory relay 47 which is connected across the battery through a conductor AH1 and a conductor AH2. The conductor AH1 is connected between the relay and the positive line wire H1, and the conductor AH2 is connected between the relay and the negative line wire H12. This relay controls a trouble light 48 and a trouble bell 49, the relay having two sets of fixed and movable contacts 47a and 47b which control the light 48 and 47c and 47d which control the trouble bell 49. The contacts are normally open and become closed upon a reduction of the current to such an extent that the relay 47 becomes for all practical purposes deenergized. The circuit through the contacts 47a and 47b and controlling the light 48 includes a conductor AI1 which connects the movable contact 47b to the conductor Z2 which, as here-

tofore described, is connected through the contacts 31d-31e of relay 31 to the negative wire. This negative wire is connected in common with the negative side of the six and twelve volt batteries. The stationary contact 47a is connected to one side of the lamp 48 through a conductor A12 and the other side of the lamp is connected through a conductor A13 to the positive side of the six volt battery. It will therefore be apparent that upon the deenergization of the relay 47 and the engagement of the contacts 47a and 47b the lamp 48 is connected across the six volt battery. The circuit to the trouble bell 49 includes the conductor A11 to which the movable contactor 47d of the relay 47 is connected in common with the movable contactor 47b. The stationary contact 47c is connected by a conductor A11 to one side of the bell 49 and the other side of the bell is connected to the conductor A13 and thus to the positive side of the battery. The lamp 48 and the bell 49 operate on six volts and they give an audible and visual indication that the twelve volt battery supplying power for the various relays in the systems is inadequate to effect the operation of the systems.

In order to insure the immediate operation of the signals indicating the failure of the twelve volt battery, the six volt battery is also supervised. The supervision of this battery is accomplished through a relay 50 which is connected across the battery through a conductor A11 that connects one side of the relay with the conductor A13 and a conductor A12 which connects the other side of the relay to the common negative conductor H1. The relay 50, like the relay 47 supervising the twelve volt battery, has two pairs of fixed and movable contacts 50a and 50b and 50c and 50d. The movable contact 50c of the relay 50 is connected to the conductor Z2 in common with the movable contactors of the relay 40. This contact 50c is therefore connected to the negative line wire H12. The cooperating fixed contact 50d is connected in common with contacts of other supervisory relays to the conductor Z3 and thus to one side of the trouble bell 35, the other side of which is permanently connected to the positive side of the twelve volt battery. Through these contactors 50c and 50d the relay 50 may effect the operation of the trouble bell 35 when the relay is deenergized. The contacts 50a and 50b are included in a circuit with a trouble light 51. The movable contact 50b is connected in common to the conductor Z2 and the stationary contact is connected to one side of the lamp 51 by a conductor A11. The other side of the lamp 51 is connected by a conductor A12 to the conductor A13 and thus to the positive side of the twelve volt battery. The circuits just described are completed upon the deenergization of the relay 50 due to the failure of the battery 46. Upon the completion of these circuits, the common trouble bell 35 is sounded and the particular trouble light 51 designating the particular source of trouble is lighted.

It is to be noted that the operation of the trouble signals is dependent upon the continued

inaction of the relay 25 or 31 which controls the warning signals.

From the above description of the illustrated systems it will be apparent that distinctly different warning and trouble signals are transmitted over a single pair of lines to a remote point and this pair of lines is electrically supervised such that when it is injured, a distinctly different signal from any of the signals transmitted over the line is operated to indicate this trouble. The value of being able to use a single pair of wires for the transmission of these signals and to supervise this transmission line will be readily apparent to those skilled in the art, the economy of installation being the predominant feature and the reduction in the possibility of trouble being another dominant feature. While within the property protected by the system herein disclosed, there may be numerous warning signals and devices as disclosed in the aforementioned copending applications which are also under electrical supervision, trouble with these devices which are inherently local in the system to the protected property is not transmitted to the remote point. If the protected property is occupied, trouble in the inherently local devices will be registered at the property and can be there corrected. If the building is unoccupied it is immaterial whether these inherently local warning and signaling devices are operated, for they are principally for the purpose of providing an immediate and orderly evacuation of the building.

It is obvious that various changes may be made by those skilled in the art in the details of the system illustrated in the drawings and described immediately above within the principle and scope of the invention as expressed in the appended claim.

I claim:

In electrical signal systems, a source of electrical energy, a plurality of systems each including two signals distinctive to each system and a third signal common to the several systems, each signal being adapted upon operation to indicate the existence of a particular condition, and each system including a means for effecting the operation of each signal independently comprising a closed electrical circuit including a source of electrical energy, electrically actuated means operative upon opening the closed circuit for effecting the connection of the first mentioned signal to the source of energy, other electrically actuated means operative upon the successive opening and closing of the closed circuit for effecting the connection of said second mentioned signal to the source of energy and additional electrically actuated means operative upon shunting a portion of the circuit for effecting the connection of the common signal to the source of energy, and means associated with one of said systems operative upon the operation of said last mentioned means for rendering the other control circuit ineffective to effect the operation of the common signal.

WILLIAM D. LINDSEY.
